Primary Examiner—Mitchell Siegel*Assistant Examiner*—Carol Rademaker*Attorney, Agent, or Firm*—Thomas A. Marcoux[57] **CLAIM**

The ornamental design for a spoon blank with detachable spoons, as shown and described.

DESCRIPTION

The FIGURE is a top view of the spoon blank with detachable spoons.

The dotted lines shown in the drawing represent tear lines. The sides and bottom of the spoon blank with detachable spoons not shown in the drawing form no part of the claimed design.
